UNITED STATES PATENT OFFICE.

CHARLES L. HOGUE, OF SAN FRANCISCO, CALIFORNIA.

OPTOMETRIST'S TRIAL-FRAME.

SPECIFICATION forming part of Letters Patent No. 748,782, dated January 5, 1904.

Application filed June 17, 1903. Serial No. 161,903. (No model.)

To all whom it may concern:

Be it known that I, CHARLES L. HOGUE, a citizen of the United States, and a resident of the city and county of San Francisco, in the State of California, have invented a new and useful Optometrist's Trial-Frame, of which the following is a specification.

This invention is designed for the use of the specialist whose calling it is to diagnose and remedy the deficiencies of vision, and it is intended to supply him (or her) with a reliable eye-testing instrument by means of which the nature and extent of such deficiencies can be quickly as well as accurately ascertained and which not only will aid in the selection of the corrective lenses to apply, but will further indicate how to construct and shape the frame therefor in order to secure a perfect fit of the glasses and true visual-mentation or rectification.

The details of the invention and manner of using it will be explained with reference to the accompanying drawings, which form an inseparable part hereof, and in which all similar elements are designated by similar letters throughout the various figures.

Figure 1 of the said drawings is a front elevation showing one embodiment of my invention aforesaid. Fig. 2 is an enlarged view 30 of one of the two lens-holders comprised in Fig. 1 and is partially broken and sectioned to show the means employed for bringing and setting the said holders and lenses therein each into the required position. Fig. 3 is a 35 partly-broken and sectioned edge view of the other lens-holder, taken from the line A B of Fig. 1, but enlarged to the scale of Fig. 2. Figs. 4 and 5 are details of a clutching device used in connection with each lens-holder. 40 Fig. 6 illustrates the application of the instrument in side elevation. Figs. 7 and 8 are respectively a front elevation and a side view representing a modification of the invention.

In the form of the invention illustrated in Figs. 1 and 6 I support the lens-holders from the top of the head by means of a light flat band of sheet metal—*e. g.*, nickelized brass or steel—which is suitably arched to conform to the crown and is preferably made in short 45 sections, as a a^2 a^3 , that are jointed together, so as to enable the instrument to be folded. The section a laps over and is adapted to

slide upon the section a^2 , the former having a central longitudinal slot a^4 and the latter being provided at one end with side lugs or 55 flanges a^5 , that grasp the edges of said section a , and with a centrally-located screw a^6 , passing upward through the slot therein and engaged by a nut a^7 above the same. The section a^8 is joined to the other end of a^2 by 60 a plain pivot a^9 . This construction, it will be observed, not only admits of folding when the instrument is to be carried in the pocket or is not in use, but further enables the said arched band to be lengthened or shortened, 65 as may be required, to accommodate the head of the person whose eyes are to be fitted with glasses. In practice the several members or sections of this band are usually drawn out, so that it will extend from a middle point on 70 the forehead slightly above the eyebrows to a similar point on the lower back part of the head, or, say, from the mesophryon to the occiput, following the median cranial line. The band is properly made wide or enlarged or extended laterally at both ends to afford stable 75 bearings on both the forehead and back part of the head as also to furnish suitable points of attachment for the lens-holders and a convenient means for anchoring the instrument and 80 maintaining it in correct position on the head. The requisite width or enlargement or extension of the band for these purposes may be provided or produced in several ways. I provide the same in the present form of the 85 invention by using plates a^9 a^{10} , which are set squarely across the extremities of the band, as shown. The front plate a^9 is firmly secured to the forward end of the section a —for instance, by a screw and nut, as suggested in Fig. 1—and it may be more or less spaced or separated therefrom, as seen in Fig. 6, by blocking or otherwise. It is slightly curved and furnished with gutta-percha cushions a^{11} , one at each end, to adapt it to narrow 95 as well as to large foreheads, these cushions enabling the forward end of the arched band to rest with adequate stability on all foreheads and besides affording an empty space into which the narrower ones can project between them. The back plate a^{10} is pivoted to the rear end of the section a^8 and may be turned parallel or in line therewith in folding the instrument. The several joints

can be sufficiently tightened to keep the band-sections rigidly in line when the instrument is unfolded, or, if preferred, the sections can be made to interlock by any known means.

5 The lens-holders before mentioned are counterparts one of the other, and therefore the description of a single holder will suffice to convey a proper understanding of the construction and operation of either holder and 10 the adaptation thereof for the reception of the lens or lenses for the right or the left eye, as the case may be. Each holder is a compound holder, in that it is adapted to receive two lenses which can be used single or combined in various relations and will be sections of a sphere, cylinder, or prism, according to the defect of vision to be corrected, such as myopia, hypermetropia, astigmatism, &c. Each is composed of two rings *b* and *c*, 15 flanged one into the other, the former relatively fixed and the latter revoluble therewith. (See Figs. 2 and 3 for details.) The latter-named ring is provided with cogs *c*² around its outer edge to enable it to be revolved by means of a pinion *c*³, hereinafter more particularly referred to. The lenses, as *d*, only one of which is shown in Figs. 1 and 3, are held each on the outside of its respective ring *b* or *c* by a curved spring *d*², 20 and one or more posts or equivalent stops or abutments *d*³ *d*⁴, arranged to bear on opposite or suitably-distant points around the metallic rim *d*⁵, with which each lens is ordinarily provided. Either ring may carry the 25 spherical or cylindrical or prismatic lens, since evidently the correct angular relation between the first and second or third of these lenses for any given case can be ascertained by revolving either lens. The angle is determined by a scale *e*, consisting of a graduated arc overlying or formed upon a small segmental plate or flange *e*², that projects inwardly from within the upper outer side or half of the stationary ring *c*. It will be 30 seen that the scale *e* is so located that the axial line of a cylinder or prism can be brought into exact register with any graduation-line thereon, and the correspondence can be noted with the utmost precision, 35 whether the lens be placed before or behind the scale—that is, on either side of the holder—on ring *b* or on ring *c*. This location of the scale is important, as it affords the only safe means of determining the angle sought, involving no guesswork, as when the scale is located outside the lens-holder, in which case the readings are seldom, if ever, accurately made, varying as much as two and one-half degrees and more from what my 40 improved instrument shows they should be.

I suspend the above-described lens-holders each from its respective side of the aforementioned band or arched support by means of crank-shafts *f*, which are journaled in 45 sleeve-bearings *f*², disposed longitudinally of the plate *a*⁹, one at each end, and held at a

short distance therefrom by posts *f*³. These shafts are slidable lengthwise in their said bearings, and thus can be moved in or out to correspondingly move the lens-holders and 50 effect the proper centering of the lenses therein. As one shaft is provided for each lens-holder, each can be slid independently of the other, and therefore enables the operator to secure differential pupillary adjustment. 55 Each shaft can at the same time be rocked by its crank *f*⁴, so that each lens can be carried forward or back to accommodate a prominent or a deep-set eye, as the case may be. This movement of either lens is also independent, permitting a difference of adjustment corresponding to any variation there may be and which is frequently found to exist in the position of the two eyes. After being set in the requisite position each shaft is 60 clamped by means of a set-screw *f*⁵. The tilting or oscillating of the lens either forward or backward to bring it properly before the eye—that is to say, at right angles to the line of vision—whether the spectacles or eyeglasses be fitted for reading or seeing at a 65 distance is accomplished in each instance by moving the connection of its holder with the crank-shaft, which connection consists of a tubular rock-shaft *g*, secured at one end to a 70 box *b*² on the ring *b* and passed through the crank-wrist *f*⁶, which latter is made hollow to receive the said rock-shaft. This shaft *g* is rocked by a nut *g*² engaging its outer end, and it is held in fixed position after adjustment 75 by a clutch, shown in detail in Figs. 4 and 5 and consisting of two disks *g*³ *g*⁴, one formed on the inner end of the wrist *f*⁶ and having a radial ridge *g*⁵ and the other located opposite on the outside of the said box *b*² and provided with radial grooves or corrugations *g*⁶ 80 to receive the said ridge. By screwing the nut *g*² tightly on the shaft *g* the latter is drawn out through the wrist *f*⁶ and the two disks *g*³ *g*⁴ become wedged or locked together 85 in such a way as to securely maintain the thereto-connected lens-holder in its given position.

The above-named box *b*² contains the previously-mentioned pinion *c*³, which, as before stated, is employed to impart motion to the ring *c* and revolve it, with its lens, over the ring *b* and its lens and scale in each compound holder when the same is correctly positioned. This pinion is preferably placed at 90 right angles to the cogged rim of the ring *c*, with which it is held in mesh. It is rotated to revolve the ring by means of a spindle *c*⁴, that passes through the tubular rock-shaft *g* (and superlying wrist *f*⁶) and carries a nut 95 *c*⁵ on its outer end.

It is manifest that the vertical adjustment of the pair of lens-holders and their lenses is very simply, quickly, and conveniently secured by sliding the arched support back or 100 forth along the mesial line of the head from the glabella to the foramen magnum, or vice

versa. This is the only vertical adjustment necessary, except in those very rare cases when the subject has one eye higher (or lower) than the other, in which cases a different adjustment of the lens is required for each eye.

5 Although my invention contemplates means for effecting such differential adjustment of the lenses vertically, it is not deemed of sufficient importance to illustrate these means at the present time, as it is believed that most practitioners will prefer the instrument as now shown and will rely on other easy ways of gaining the required adjustment in such normal cases. However, I shall state that 15 the present form of the invention can be easily made to provide for the adjustment in question by making the cranks each in two parts telescoping or slidable one upon the other, so that the cranks may be lengthened 20 or shortened and the lens-holders correspondingly raised or lowered independently one of the other, and to the optometrist who will so order the instrument will be furnished in that form.

25 Figs. 7 and 8 show the lens-holders suspended from a different support. The arched support is not used in this form of the invention, the same being replaced by parallel superimposed rods h and i i^2 , designed to be 30 supported from the nose and ears of the subject by means of a nose-piece j and temples k . The nose-piece is vertically adjustable and the temples are hinged, as at k^2 , to uprights l , which receive the ends of the said 35 rods. The crank-shafts of the lens-holders in this modified form of the invention, are journaled in slidable bearings h^2 on the lower rod h , and the latter are moved independently one of the other by turning the upper rods 40 i i^2 , which are respectively provided with right and left screw-threads for the purpose and engage corresponding threads in suitable lugs or projections of the said slidable bearings. Otherwise the invention is not changed 45 from what has already been described, comprising the same parts, which are designated by the same reference characters.

What I claim, and desire to secure by Letters Patent of the United States, is—

50 1. An optometrist's trial-frame comprising a suitable support, and lens-holders suspended therefrom, each by an independently movable and adjustable crank connection, said lens-holders being also adjustable in and relatively to their respective connections.

2. An optical trial-frame comprising a head-rest having the central extensible arched portion, the rear portion, the front portion conforming to the shape of the head secured 60 upon the end of the arch portion, lens-holders supported on said front portion, removable lens-frames in said holders, and means for adjusting said lens-holders relatively thereto.

65 3. An optical frame comprising a head-rest, a front end piece arranged to rest upon the forehead, bars independently slidably hori-

zontally of the forehead-piece, a lens-holder supported by each bar, and means for clamping either bar in any desired position, substantially as described.

4. An optical frame comprising a head-rest, a lens-holder, a hanger supporting said lens-holder, a bearing on said head-rest in which said hanger slides transversely and in which it is vibratable, and means for clamping said hanger in any desired position, substantially as described.

5. An optical trial-frame comprising a head-rest, a hanger supported therefrom, a lens-holder having an arm pivotally mounted in the hanger, means for clamping said arm in any desired position, a lens, and a frame therefor rotatably mounted in said lens-holder, said frame having gear-teeth, and a shaft passing through the center of the arm of the lens-holder and having a pinion engaging said gear-teeth, substantially as described.

6. An optical trial-frame comprising a head-rest, a hanger supported therefrom, a lens-holder having a hollow arm pivotally mounted in the hanger, a lens, a frame therefor rotatably mounted in said lens-holder, said frame having gear-teeth, and a shaft in said hollow arm having a pinion engaging said gear-teeth, substantially as described.

7. An optical trial-frame comprising a support, and a pair of lens-holders secured to said support adjustable independently one of the other to and from the eye.

8. An optical trial-frame comprising a support, independently-adjustable hangers supported therefrom, and lens-holders adjustably secured to said hangers.

9. A trial-frame comprising a suitable support, lens-holders suspended therefrom each by an independently-adjustable hanger, said lens-holders being also adjustable in or relatively to their hangers.

10. A trial-frame comprising a suitable support, independently-adjustable hangers suspended therefrom, and lens-holders rotatably secured in the ends of said hangers.

11. A trial-frame comprising a suitable support, a pair of independently horizontally adjustable hangers suspended therefrom and rotatably secured thereto, and lens-holders adjustably secured to said hangers.

12. A trial-frame comprising a suitable support, a pair of apertured posts secured thereto, independent cranked hangers engaging said apertured posts, lens-holders adjustably secured to said cranked hangers and means for adjustably securing said crank-hangers in said apertured posts.

13. A trial-frame comprising a suitable support, independently-adjustable hangers supported therefrom, lens-holders having hollow arms pivotally mounted in the hanger, a lens, a frame therefor, rotatably mounted in said lens-holder, said frame having gear-teeth, and a shaft in said hollow arm having a pinion engaging said gear-teeth.

14. A trial-frame comprising a support, a hanger supported therefrom, a lens-holder the arm of which is pivotally mounted in said hanger, a lens, a frame therefor rotatably mounted in said lens-holder, said frame having gear-teeth, a shaft passing through the center of the arm of the lens-holder and having a pinion engaging said gear-teeth, and means for locking said shaft against rotary movement.

15. A trial-frame comprising a support, a hanger supported therefrom, a lens-holder the arm of which is pivotally mounted in said hanger, a lens, a frame therefor rotatably mounted in said lens-holder, said frame having gear-teeth, a shaft passing through the center of the arm of the lens-holder and having a pinion engaging said gear-teeth, and a

clutch interposed between the shaft and the arm of the lens-holder.

16. A trial-frame comprising a support, a lens-holder supported therefrom, a lens, a frame therefor rotatably mounted in said holder, and an indicator secured within holder in the rear of the lens.

17. A trial-frame comprising a support, a lens-holder supported therefrom, said lens-holder comprising a stationary ring and a ring rotatable on said stationary ring, a lens secured to each of said rings, and an indicator secured to one of said rings within the holder and intermediate said lenses.

Corrections in Letters Patent No. 748,732.

It is hereby certified that in Letters Patent No. 748,732, granted January 5, 1904, upon the application of Charles L. Hogue, of San Francisco, California, for an improvement in "Optometrist's Trial-Frames," errors appear in the printed specification requiring correction, as follows: In line 14, page 3, the word "normal" should read *abnormal*; and that the said Letters Patent should be read with this correction therein that the same may conform to the record of the case in the Patent Office.

Signed and sealed this 9th day of August, A. D., 1904.

[SEAL.]

E. B. MOORE,
Acting Commissioner of Patents.

14. A trial-frame comprising a support, a hanger supported therefrom, a lens-holder the arm of which is pivotally mounted in said hanger, a lens, a frame therefor rotatably mounted in said lens-holder, said frame having gear-teeth, a shaft passing through the center of the arm of the lens-holder and having a pinion engaging said gear-teeth, and means for locking said shaft against rotary movement.

15. A trial-frame comprising a support, a hanger supported therefrom, a lens-holder the arm of which is pivotally mounted in said hanger, a lens, a frame therefor rotatably mounted in said lens-holder, said frame having gear-teeth, a shaft passing through the center of the arm of the lens-holder and having a pinion engaging said gear-teeth, and a

clutch interposed between the shaft and the arm of the lens-holder.

16. A trial-frame comprising a support, a lens-holder supported therefrom, a lens, a frame therefor rotatably mounted in said holder, and an indicator secured within holder in the rear of the lens.

17. A trial-frame comprising a support, a lens-holder supported therefrom, said lens-holder comprising a stationary ring and a ring rotatable on said stationary ring, a lens secured to each of said rings, and an indicator secured to one of said rings within the holder and intermediate said lenses.
